UNITED STATES PATENT OFFICE.

CORA B. LOVETT, OF OAKLAND, CALIFORNIA.

SHAMPOO-TRAY.

No. 928,313.

Specification of Letters Patent.

Patented July 20, 1909.

Application filed October 21, 1908. Serial No. 458,864.

To all whom it may concern:

Be it known that I, CORA B. LOVETT, a citizen of the United States, residing at Oakland, in the county of Alameda and State of California, have invented certain new and useful Improvements in Shampoo-Trays, of which the following is a specification, reference being had therein to the accompanying drawing.

10 This invention relates to a shampoo tray and a support therefor, and has for its object the provision of means for facilitating the clamping and supporting of a tray upon a support.

15 Another object of this invention is the production of a tray which will allow the neck of the person being shampooed to extend into the tray.

Still another object of this invention is the 20 production of means for facilitating the discharging of liquid from a tray.

With these and other objects in view, this invention consists of certain novel constructions, combinations, and arrangements of 25 parts, as will be hereinafter fully described and claimed.

In the drawings: Figure 1 is a rear view of the tray-support with the tray in section. Fig. 2 is a side view of the tray-support, with 30 the tray in section. Fig. 3 is a bottom plan view of the tray. Fig. 4 is a sectional view taken on line 4—4, Fig. 3. Fig. 5 is a section taken on line 5—5, Fig. 3.

Referring to the drawings by numerals, 1 35 designates a clamp, which constitutes a substantially inverted U-shaped portion 2. Between the sides of the U-shaped portion 2 is positioned an adjustable plate 3. Said plate 3 is adjusted by means of thumb-screws 4 working in screw-threaded apertures 5 in the rear side of the inverted U-shaped portion 2 of the clamp. The body portion 2 of the clamp is lined with a strip of felt 6, and the plate 3 is also lined with a 40 strip of felt 6^a to prevent the marring of furniture to which the clamp is attached. The body portion 2 is provided with an integral extension 7 upon its rear face, and between the thumb-screws 4. The integral 45 extension 7 is provided with an aperture 8,

into which is positioned a post 9, which is provided, at its upper end, with an angle-portion 9^a. The post 9 is held in the aperture 8 by means of a thumb-screw 10, which passes through an aperture 10^a and engages 55 the post 9.

Upon the post 9 is supported a tray 11, which tray is reinforced upon its under-surface by means of a Y-shaped reinforcing member 12, which is secured to the bottom 60 of the tray by any suitable fastening means, as for instance, rivets 12^a. The reinforcing member consists of outwardly-extending fingers 13, 14 and 15. At the junction of the three fingers 13, 14 and 15 is an integral extension 16, which integral extension is provided with an aperture 17, into which is positioned the upper angle-portion 9^a of the post 9. The angle-portion 9^a of the post 9 is securely held in said aperture 17 by means 65 of a thumb-screw 18.

The tray 11 is provided with an open or unobstructed end 19, which is curved slightly downward, as at 19', Fig. 4. The sides and one end of the tray are provided with flanges 75 20 and 21, which extend the entire length of the sides and around one end of the tray; the flanges being abruptly turned inwardly near the open end of the tray so as to discharge the liquid contained in the tray into a much 80 smaller receptacle than the tray. The closed end of the tray is provided with an inwardly-bowed portion or neck-receiving socket 23, which is formed intermediate of the sides of the tray. Upon each side of the 85 neck-receiving socket are straight portions 24. The flanges at the side of the tray are reinforced by means of a wire or rod 25 passing around the upper edge of said flanges and around the sides and one end of the tray, and the upper end 26 of said flange being bent 90 around said wire or rod. The flange tapers slightly, as at 27, at the discharging ends of the tray.

What I claim is:

1. In an apparatus of the class described, the combination with a tray, of a Y-shaped reinforcing member secured to said tray, an integral extension positioned at the junction 95 of the fingers of said Y-shaped reinforcing 100

member, said extension provided with a socket, a post positioned in said socket, and means for clamping said post in said socket.

2. As a new article of manufacture, a tray, 5 a reinforcing member comprising a forwardly-extending finger and a plurality of rearwardly-extending fingers secured to the bottom of said tray, a projection formed at the junction of said fingers and provided with

a socket formed therein and means positioned in said socket for securing said tray to a support.

In testimony whereof I hereunto affix my signature in presence of two witnesses.

CORA B. LOVETT.
